UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed January 14, 1925. Serial No. 2,276.

This invention relates to internal combustion engines, more particularly to the cooling systems thereof and it has for one of its objects to provide a cooling system in which the weight of fluid necessary to cool the engine shall be much reduced and the ratio of engine weight to power developed shall be thereby decreased.

Another object of the invention is to provide an engine cooling system for use on motor vehicles in which the head resistance caused by the radiator shall be materially reduced.

A further object of the invention is to provide an engine cooling system having cooling jackets or spaces surrounding the engine cylinders in which the surfaces of the jacket and the cylinder barrel shall be protected from rust and other corrosion.

Other objects of the invention will appear from the following description taken in connection with the drawings, which form a part of this specification, and in which:

Fig. 1 is a view in side elevation, partially broken away and partially in section, of a portion of an internal combustion engine illustrating the invention, and

Fig. 2 is an enlarged sectional view of a portion of the engine shown in Fig. 1.

Refinement in the design of water-cooled internal combustion engines has progressed to a point where the weight of the cooling system carried is a material factor in the ratio of engine weight to power output. Particularly is this true in engines such as are used in the propulsion of aircraft; such engines having been built in which the weight is as low as 1.5 to 1.7 pounds per brake horsepower developed, but in which the weight of the radiator and cooling water carried is 35 percent to 40 percent of the total engine weight. Ordinarily, the temperature at which the cylinder walls of an engine may be operated is limited by the boiling temperature of water at the atmospheric pressures encountered, and sufficient water must be carried with a given rate of circulation to maintain the cylinder wall temperature below this point under all power outputs, since it is essential that no appreciable loss of water by evaporation shall occur. The weight of cooling water which must be carried by an engine of given size is thus approximately fixed.

In the present invention the weight of the cooling system which must be carried by such an engine is considerably reduced, the cylinder walls being permitted to attain a higher temperature, which is, in general, beneficial to engine operation. The engine temperature may be held below such a limit by the circulation of a smaller quantity of water, and at the same time, the maximum temperature of the cooling water is not permitted to exceed the boiling point, thus preventing loss from evaporation. This result is accomplished by retarding the transfer of heat from the cylinder walls to the cooling water which is circulated around them, so that less heat is absorbed by the water. Preferably the cylinder walls are given a thin film or coating of any suitable heat retarding material, by which the flow of heat through the cylinder walls to the cooling space is checked. In this way not only is the weight of cooling water reduced, but the size of radiator required may be also reduced in proportion, thus decreasing both the weight and the wind resistance of the vehicle which is being driven. This last named feature is particularly valuable in aeronautics in which the parasitic resistance overcome represents the expenditure of a large proportion of the total power.

Referring to the drawings, at 10 is shown a portion of an internal combustion engine having a crankcase 11 on which is mounted a bank 12 of cylinders 13. As shown, the bank of cylinders 12 is formed as an integral cylinder block, but it is to be understood that the bank may consist, if desired, of individual cylinders, separately secured to the crankcase, or in groups of cylinders of any desired number, as is well understood in the art to which this invention relates. The crankcase 11 is provided with suitable bearings 14, in which is journaled a crankshaft 15, and this crankshaft is connected by connecting rods 16 to pistons 17, adapted to reciprocate in the cylinders 13 in the usual manner.

The cylinders 13 are provided with a suitable head, which in the embodiment illustrated comprises an integral head casting 18, provided with a combustion chamber 19 for each of the cylinders 13, and provided with suitable passages 21 for the circulation of cooling water; the passages 21 forming a

- water jacket for the cylinder head. Each of the cylinders 13 is also provided with a cooling space 22 formed in the cylinder block 12 to surround the cylinder, and constituting a water jacket therefor, these jackets being connected in any suitable manner, not shown. If separate cylinders are employed, each of these cylinders will have an independent water jacket, as will be readily understood.
- 10 Suitably mounted in a housing engine 10, preferably at the forward end of the cylinder block 12, is a water pump 23, adapted to maintain a forced circulation of cooling water through the jackets 21 and 22 as is readily understood. The pump 23 may be of any suitable type but is preferably of the rotary type, having a shaft 24, driven by a pulley 25 and a belt 26 from any convenient rotating part of the engine, such as the engine camshaft (not shown).
- 15 Mounted forwardly of the engine 10 is the usual radiator 27, having at its upper end an inlet 28 for heated water from the water jacket 21, and at its lower end an outlet 29, connected by suitable means, such as the conduit 31, with the intake of the pump 23. The radiator 27 has a core portion comprising air passages or tubes 32 extending from front to rear, around which the water in the radiator flows as it moves from the upper to the lower portion of the radiator, being cooled in the process, as is well understood. The forward end of the pump shaft 24 is preferably provided with a fan 33 by which the natural draught of air through the tubes 32 is augmented. The radiator inlet 28 is connected by any suitable conduit 34 with a jacket outlet 35, formed on the cylinder head block 18 and communicating with the water jacket 21.
- 20 The circulation of water through the cooling system described is well known. Water from the delivery side of the pump 23 enters a suitable distributing conduit (not shown) by means of which it is introduced into the various cylinder cooling jackets 22, through which it flows in parallel, absorbing heat from the cylinder wall. The heated water rises and enters the cylinder head jacket 21, absorbing heat from the cylinder walls and particularly from the combustion chambers 19, and flows forwardly into the outlet 35, through conduit 34 and radiator inlet 28 into the upper end of the radiator 27. Here it is subjected to the cooling action of the air passing through the tubes 32. The cooled water is drawn from the bottom of the radiator through the outlet 29 and passes through the conduit 31 into the intake of the pump 23, thus completing the cycle.
- 25 As previously explained, the volume and hence the weight of cooling water which is necessarily carried by the engine is practically established for any given maximum

power output of the engine. This volume must be sufficient to absorb the heat generated at such power output without exceeding the boiling temperature of water. In the present invention the quantity of water carried is decreased, and the temperature of the walls of the cylinders 13 is correspondingly increased by retarding the transfer of heat from the cylinders 13 to the cooling water in the jackets 21 and 22. To accomplish this the walls of the cooling spaces are coated with a thin film of heat resisting or insulating material so that the transfer of heat therethrough takes place at a much less rapid rate. Any suitable material may be used for this purpose but it has been found that certain of the phenol condensation products, such as the well known bakelite, provide a very satisfactory coating. This material is heat resistant, is waterproof, and may be repeatedly wetted and dried without cracking or other deterioration.

This material may be applied to the cylinder jackets in any suitable way. In engines having independent cylinders, in which the cooling jackets are affixed to the cylinder walls after manufacture thereof, the bakelite insulation may be applied to the inner walls of the cylinders in the form of thin sheets before attachment of the cooling jackets to the cylinder forgings, or it may be moulded in place. In engines cast en bloc, as in the embodiment disclosed herein, the insulating film may be conveniently applied in the form of a varnish. In this method of application the cooling spaces of the engine are filled with such a varnish which is allowed to stand a short time, and are then drained. Drying of the varnish film thus applied to the walls of the cooling jackets may be hastened by a draught of air from any suitable source, introduced through the pump intake and exhausting through the jacket outlet 35. After a coating of such varnish has been suitably dried, another coat may be applied in a similar manner until an insulating film 36 of sufficient thickness has been built up on the inner surfaces of the cooling spaces 21 and 22. This varnish may be prevented from entering the pump chamber by blocking off the distributing conduit during the filling and draining operations.

The varnish film 36 forms a shield between the walls of the cylinders 13 and the combustion chambers 19, and the water in the cooling spaces 21 and 22, which retards or checks the flow of heat into the cooling water. It is obvious that this will cause the cylinder walls to rise to a higher temperature, and that a smaller volume of cooling water will maintain the walls at this new temperature limit without boiling. The amount of water heretofore necessarily carried by an engine of given size and power

may therefore be materially reduced, and this not only greatly decreases the ratio of weight to horsepower of the engine but permits the use of a smaller radiator and therefore lowers the head resistance of the vehicle on which the engine is mounted.

It is also apparent that the varnish film 36 forms a protective coating for the interior of the cooling space, preventing rust 10 and other corrosion of the metal of the cylinder walls.

It will be understood that various forms 15 of the invention other than those described above may be used without departing from the spirit or scope of the invention.

What is claimed is:

1. The combination in an internal combustion engine, of a cylinder, having walls and a head, a jacket for said walls and head 20 defining therewith a cooling space adapted to contain cooling fluid, and a thin covering for said walls and head within said space and impervious to the cooling fluid to retard the transfer of heat from the cylinder 25 to said fluid.

2. The combination with an engine having cylinders and a head, and a jacket surrounding the cylinders and head adapted to contain cooling fluid, of heat retarding varnish 30 on the inner walls of said jacket adapted to delay the transfer of heat from the cylinders and head to the cooling fluid.

3. The combination with an engine cylinder having a jacket defining a cooling 35 space, of heat retarding means between the cylinder and said cooling space, said means

comprising a varnish containing a condensation product of phenol.

4. The combination with an engine cylinder having walls and a jacket defining a 40 cooling space, of a thin coating of heat retarding varnish on the cylinder and jacket walls within the cooling space adapted to affect the flow of heat through said cylinder walls to said cooling space. 45

5. The combination in an internal combustion engine, of a cylinder having walls and a head surrounded by a cooling fluid, and a thin heat-retarding covering for said walls and head adapted to prevent corrosion 50 by the cooling fluid.

6. The combination in an internal combustion engine, of a cylinder having walls and a head, a jacket for said walls and head defining therewith a cooling space adapted 55 to contain cooling fluid, and a thin coating for said walls and head in contact with the cooling fluid and adapted to resist corrosion thereby, to retard the flow of heat from said walls and head to said fluid. 60

7. The combination with an engine cylinder having a jacket defining a cooling space, of cooling fluid in said space to absorb heat from the walls of the cylinder, and a thin coating of heat retarding material 65 on said walls in contact with said fluid adapted to prevent corrosion of said walls by said fluid.

In testimony whereof I affix my signature.

LIONEL M. WOOLSON.
